MANICURING DEVICE

Ella G. Terry, Valparaiso, Ind.

Application March 7, 1950, Serial No. 148,195

2 Claims. (Cl. 132—73)

1

This invention relates to manicuring devices and more particularly to devices used in manicuring the fingernails and toenails of a human being.

In the care or manicuring of toenails and fingernails it has relatively recently become quite customary to apply a lacquer or other coating commonly known as "polish." Such polish commonly varies in color and shade, ranging from transparent relatively colorless material to deep colored translucent coatings.

Heretofore, such polish has commonly been applied to the fingernails or toenails in a liquid state by means of a brush or similar applicator. Such a method of applying polish is relatively slow and tedious, and has several inherent disadvantages. One of these disadvantages is that the polish must necessarily be applied to the nail of the digit in several strokes of the brush and for practical purposes the liquid being so applied must be of a relatively quick drying type so that it is difficult to apply the polish to the digit in a manner whereby a smooth coating is afforded. Another disadvantage is that because of the necessary quick-drying characteristics of the liquid polish, it is substantially impossible to apply the polish in a continuous smooth coating, the brush strokes necessarily overlapping each other and affording a stratified coating which is especially subject to peeling or chipping. A further disadvantage is that although the liquid polish is of a quick-drying type, an appreciable length of time is required for the polish to completely dry after being applied to the nails, during which time the person upon whose nails the polish has been applied must carefully keep her nails out of contact with other objects so as not to spoil or mar the desired lustrous finish when the polish has completely dried. Yet another disadvantage of applying liquid polish in the aforementioned manner is that in most instances the polish is applied by an average individual who is not especially skilled in the art, and must be applied by that individual on both hands, this necessitating that the polish on the nails of the left hand be applied with a brush held in the right hand, and vice versa, and the average individual is usually not skilled in the use of one hand or the other for careful, relatively skillful work of this nature, and, as a result encounters considerable difficulty in so applying the polish in a desirable manner.

A further disadvantage is that the nails of the average human being are normally relatively hard and brittle so that the nails themselves are relatively easily chipped or split to thereby mar the polished appearance thereof, and, furthermore,

2

the nails being hard, the polish itself is especially subject to being chipped from the nails when the nails strike other hard objects.

It is a primary object of my invention to overcome such disadvantages and to afford means for applying polish to fingernails and toenails in a novel and expeditious manner whereby the average individual may quickly and easily apply polish to his or her nails.

Another object is to afford a novel manicuring device wherein polish applied to fingernails or toenails is padded to thereby cushion the polish against shock from impact of the nail with hard objects and thereby afford efficient protection against chipping of the polish from the nail.

Yet another object of my invention is to afford a novel pre-formed nail polish which may be quickly and easily applied to the nails of the digits of an individual by that individual in a novel and expeditious manner.

A further object of my invention is to afford a novel preformed nail polish of the aforementioned type which may be quickly and easily applied to the nails of an individual and, if desired, may be removed and later replaced on the nails of that individual.

Another object is to provide a novel pre-formed nail polish of the aforementioned type which, when applied to the nails, affords a waterproof coating therefor which is not loosened from the nails by the normal bathing or washing of the hands or the use of soap and water customary in normal housework.

I am familiar with the previously known manicuring devices of the type wherein fingernail polish may be applied by means of a decalcomania. I am also familiar with previously known manicuring devices whereby dried fingernail polish may be applied directly to the nails by means

of a water-soluble adhesive. However, although such articles overcome a few of the disadvantages experienced in the application of nail polish to the nails in liquid form by means of a brush, or the like, not all of such disadvantages are overcome, and, in addition such system of applying polish has additional inherent disadvantages.

Thus, for example, it will be seen that the decalcomanias and the dried film are each held by water-soluble adhesive so that the polish applied to nails in this manner is definitely not waterproof. Furthermore, as is well known to those skilled in the art, decalcomanias are relatively difficult to apply and position correctly even when using two hands and when an individual is limited to the use of one hand in applying a decalcomania to the fingernail of the

other hand, such activities are replete with difficulties to say the least. Also, with respect to the manicuring articles heretofore known wherein dried fingernail polish may be applied directly to the nails by means of a water-soluble adhesive, it will be appreciated that such a film is extremely brittle and difficult to handle. In addition, it will be seen that in the case of both the decalcomania and the directly applied dried film of fingernail polish, the polish is mounted directly on the fingernail and is therefore subject to cracking or chipping if the fingernail itself is cracked or chipped, and, in addition, is not cushioned on a fingernail against impacts resulting from the fingernail striking other hard objects and is therefore subject to being relatively readily chipped by such impacts.

It is an object of my invention to afford a manicuring device of the aforementioned type wherein a film of dried fingernail polish is disposed on a suitable base member or pad on which a pressure-sensitive waterproof adhesive is disposed for securing the pad and film of polish to a fingernail or toenail, the device being pre-formed into the shape of the nail to which it is to be applied, when that nail is disposed in flattened position so that when the device is applied to the nail on the hand of an individual, the device conforms itself substantially exactly to the shape of the nail to which it is so applied.

Other and further objects of the present invention will be apparent from the following description and claims and are illustrated in the accompanying drawings which, by way of illustration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 illustrates the manner in which articles of manufacture embodying the principles of my invention are preferably packaged for marketing;

Fig. 2 is a longitudinal sectional view through one of the manicuring devices shown in Fig. 1;

Figs. 3, 4 and 5 are views showing different steps in the application of my device to a finger-nail; and

Fig. 6 is a view somewhat similar to Fig. 2 but showing a modified form of my device.

In the drawings, a manicuring device or article 10 is shown to illustrate a preferred embodiment of my invention. The device 10 comprises, in general, a readily flexible body member or base sheet 12 on one face of which is disposed a coating of a suitable pressure-sensitive adhesive 14, and on the other face of which is disposed a suitable coating or film of dried fingernail polish or toenail polish 16, as will be discussed in greater detail hereinafter.

The device 10 has a front edge portion 18, a rear edge portion 19 and two side edges 21, 22. Each of the devices 10 are preferably so formed that they correspond substantially to the shape and size of the respective nail on which the device is to be applied, so that after application of the device to the nail a minimum amount of trimming will be necessary.

As will be appreciated by those skilled in

the art, the usual preferred shape of well-dressed fingernails is the common and popular almond-shape wherein the forward portion of the fingernail projects somewhat from the end of the finger and tapers to a rounded or modified point as is shown in dotted lines in Figs. 3 and 4.

In constructing devices of this character I have found it is desirable to afford a device which is somewhat, but only slightly, longer than the fingernail to which the device is intended to be applied, and wherein the device is so shaped that when applied to the fingernail the rear portion of the device is disposed on the fingernail in close fitting engagement to the peronychium of the finger. The fingernail of the average individual is, of course, somewhat rounded or arched outwardly and inasmuch as the device 10, as packaged for marketing, is substantially flat, I have found that it is desirable to so construct the device 10 that the side edges 21 and 22 and the front edge 18 taper or flare outwardly somewhat from the rear edge portion 19, in substantially a fan-shape, or shield shape, as best shown in Fig. 1, to thereby as closely simulate the shape of that portion of the nail defined by the peronychium as possible when that nail is disposed in flattened position.

The base sheet 12 of the manicuring device 10 may be constructed of any suitable material such as, for example, silk, cotton, or rayon cloth or fabric, or similar woven fabrics, or thin sheet rubber, paper, plastics, or the like. However, I prefer to use relatively thin sheets of suitable fabric such as, for example, cotton and, in making the device 10, each base sheet 12 is formed so as to closely resemble the size and shape which would be assumed by that portion of a nail to which the device is to be attached, if that nail were removed from the digit and flattened out.

Preferably, the upper face of the base sheet 12 to which the film or coating 16 is to be applied, is glazed or relatively smooth so that the film 16, when applied thereto, presents a smooth outward finish.

Also, the base sheet 12 is preferably waterproof or water repellent and for this purpose I prefer to use sheet material such as embodied in any one of several suitable waterproof adhesive tapes which are heretofore known such as, for example, a base sheet made in accordance with the disclosure of United States Letters Patent No. 2,187,563, granted to Raymond E. Thomas on January 16, 1940. The following example illustrates a suitable material, and the method of making the same, which may be used to form the base sheet 12 in the practice of the present invention, the quantities being given by weight:

A plain weave cotton fabric weighing approximately 3.7 ounces per linear yard 40 inches wide, having a yarn count of 80 x 80 and bleached by conventional methods may be rendered water repellent by giving it three ends through an impregnating bath consisting of:

	Per cent
Emulsion 9	89.3
Water	10.7

The material referred to above as "Emulsion 9" is an emulsion comprising deacetylated chitin, paraffin wax, glacial acetic acid, and aluminum acetatem and whose preparation is described in Example IX of United States Patent 2,047,217 of July 14, 1936. During the impregnation of the cloth, the impregnating bath is maintained at a temperature of approximately 170° F. (77° C.). The impregnated fabric may then be dried in a

tenter frame holding the fabric to the original width.

The fabric before treatment will absorb water in much the same way as blotting paper. After the above described treatment, it is "non-wetting" and "water repellent."

The terms "waterproof" and "water repellent" are used to describe the ability of the fabric to withstand a shower of water on its surface without any penetration of water through the fabric to the reverse side. A suitable procedure for determining water repellency is that described by Matthews in "The Textile Fibers," 4th Ed. (1924) Wiley—page 991. This test is described as follows:

"Dry the pieces of fabric used in conducting the funnel test at 45° C. for 24 hours, hang in laboratory over night and clamp loosely in frame. Set the frame in a holder attached to a trough at an angle of 45 degrees. Allow clear tap water at room temperature to fall a height of 6 feet upon the central portion of the fabric, covering an area of about 8 inches in circumference for 24 hours, from a 2 1/4 inch brass spray nozzle having 25 holes, each 1.9 (0.75 in.) mm. in diameter, at a rate of 1000 cc. per minute.

"Inspect the condition of the underside of the fabric at the end of five minutes, one-half hour, one hour, three hours, seven hours, and twenty-four hours. Note at each inspection whether the under surface is dry, damp or wet with no dripping; damp or wet with dripping."

It will be appreciated that a water repellent fabric is not necessarily resistant to the passage of water under hydrostatic pressure.

The waterproof adhesive 14, may be of any suitable type of pressure sensitive material, such as, for example, a normally tacky, pressure sensitive adhesive made according to the disclosure of the aforementioned Raymond E. Thomas Patent No. 2,187,563. The following example illustrates a suitable adhesive composition which may be used in the practice of the present invention, all parts by weight:

	Per cent
India rubber	8.1
Rosin	7.7
Zinc oxide	12.1
Wool fat	12.1
Benzene	60.

In compounding the adhesive, the rubber is mixed with the benzene in the ratio of 14.3 parts of the former to 85.7 parts of the latter until a uniform colloidal solution is produced. The rosin is dissolved in its own weight of benzene and strained. The zinc oxide is dried at 100° C. and mixed with benzene in the ratio of 73.4 parts to 26.6 parts of benzene until a thick paste is formed. The wool fat may be incorporated into the zinc oxide paste, which is then thoroughly mixed with the rosin and rubber solutions and the product allowed to stand a few hours before spreading.

The coating operation, wherein the adhesive 14 is applied to the base sheet 12, may be carried out by passing the impregnated fabric through a series of three calender rolls adjusted so that not less than 1.5 grams of the non-volatile components of the pressure sensitive mass is spread over each 100 square centimeters of the cloth. This is equivalent to 4.4 ounces per square yard.

The preferred fabric for making the base sheet 12 is known as Stevens cloth, and is a plain (or sheeting) weave having a yarn count of 80 x 80 as heretofore set forth. However, other fabrics

may be satisfactorily used if desired, such as, for example, broadcloth and special weave fabrics such as pajama check.

A wide variety of pressure sensitive adhesives may be employed in the present invention. Those set out herein are merely illustrative, many such compositions being known to the workers in the art. For further details reference is made to "The Chemical Formulary," vol. 2—Bennett, and "The Pharmacopeia of the United States" eleventh decennial revision (1936). Such compositions usually consist of rubber, rosin or resins, wax or oil, and a filler or absorbent powder (for example, zinc oxide, orris root, and starch).

For convenience in spreading, and for best appearance, the adhesive mass should be free from nodules. Satisfactory results may be obtained with compositions containing approximately 20% of pure rubber based on the non-volatile components of the composition. Zinc oxide, if used, preferably constitutes 20% to 30% of the composition on the same basis. The volatile solvent of the spreading mass may vary widely, although 40% to 50% is usually used.

The amount of pressure sensitive adhesive applied usually runs between 5.5 and 7. ounces per square yard. The intermediate range of 6.2 to 6.7 has been found to be the most desirable for ordinary use.

The polish 16 may be of any one of suitable nail polishes or lacquers available on the market and is preferably applied to the base sheet 12 by spraying, although, of course, as will be appreciated by those skilled in the art, the polish may be applied to the base sheet 12 by other suitable methods such as, for example, printing methods and the like.

In packaging the devices 10 for marketing the same, the devices 10 are preferably mounted on a suitable backing sheet 26 which may be constructed of any suitable material such as, for example, a thin layer of cotton, such as crinoline, the backing sheet 26 preferably being relatively

stiff and of a relatively wide mesh to thereby afford a member from which the adhesive 14 may be readily detached by relatively gently pulling on the device 10 to be removed therefrom, and the backing sheet member being substantially transparent. In such packages, the devices 10 are preferably mounted on the backing sheet 26 in sets of five, one for each of the digits on the foot or hand for which the devices of that particular package are intended. It will be understood, of course, that these packages will be made up in several different sets, according to various average sizes of fingernails of individuals and, an individual purchasing the set may, by placing the backing sheet 26 over the fingernail, for example, choose the size which most closely approximates the size and shape of her fingernail.

In applying the device 10 to the nail for which it is intended, the individual may remove the device 10 from the backing sheet 26 and place it gently on the nail on which it is to be finally applied so as to determine whether the device needs any additional trimming before application to the nail. If the device is an exact fit for the nail of the individual, wherein the side edges 2 and 22 and the rear edge 19 are disposed inwardly of, adjacent to, and closely follow the outline of, the peronychium of the digit, the device 10 may then be firmly pressed on to the nail of the digit and carefully smoothed thereonto. Preferably, 75 when so disposed on the digit, the front edge 18

of the device 10 will project outwardly somewhat beyond the forward edge of the fingernail 24, as shown in Fig. 3, and, after being properly applied, may then be trimmed off to conform to the leading edge of the finger 24. If desired, the individual may trim both the fingernail and the device 10 at the same time.

In many instances, the individual desires to apply coatings of polish to the nails of her digits in a manner wherein the polish completely covers the nail within the outline of the perionychium, and in such instances, the device 10 may be applied to the nail in the manner illustrated in Fig. 3, wherein the outer edge of the rear end portions of the edges 21 and 22 of the device 10, and the rear edge 19, exactly follow the outlines of the perionychium. However, in some instances, it is desired to apply polish to the nails in a manner whereby either the actual "half-moon" is exposed or a simulated half-moon is formed, and in these instances, this may be readily accomplished with my device by shaping the rear edge 19 of the device 10 so as to afford a space for viewing the real or simulated half-moon, as shown in Figs. 4 and 5. This may be readily accomplished on my device 10 by using the usual manicuring scissors to form the half-moon, indicated at 28, Figs. 4 and 5, before applying the device 10 to the nail, my device 10 being especially well adapted for so shaping the rear edge portion thereof, because of the ready manner in which it may be handled without danger of breaking or otherwise spoiling the appearance thereof.

After so shaping the half-moon 28 on the device 10, the device 10 may then be applied to the fingernail in the same manner as previously set forth with respect to the device shown in Fig. 3, the device 10 being applied to the nail in the manner wherein the forward edge portion 18 thereof projects outwardly beyond the forward edge portion of the nail 24, as shown in Fig. 4, and then trimmed to the edge of the nail as shown in Fig. 5. It will be noted that after the manicuring device 10 is applied to the fingernail, it loses the fan-shape or shield-shape of the flattened devices shown in Fig. 1, and upon being curved over the nail in close fitting relation thereto assumes the "almond"-shape shown in Figs. 3-5 which is the popular shape for fingernails.

With polish applied in the aforesaid manner, it will be seen that the base sheet 12 affords an effective pad for the polish 10 to thereby cushion it against shock when the nails are struck against hard objects, and thereby reduce the possibility of such impacts causing the polish to be chipped from the nails. Also, it will be seen that a manicuring device constructed in accordance with my invention is substantially waterproof and will not loosen by the immersion of the hands in water while bathing, washing dishes, or doing the other usual household tasks.

Also, it will be seen, that the device 10 affords a novel and efficient means for applying fingernail polish which enables the wearer to play the piano, operate a typewriter, etc., without the usual danger to the polish inherent in such activities. An additional feature is that if desired, the manicuring device 10 may be removed from the fingernails and stored in a suitable place, such as, for example, on a sheet of glass or the like, so as to protect the adhesive 14, and may then be reapplied to the fingernails at a later date.

In the modified form of my invention shown in Fig. 6, the device 10a shown therein is shaped and formed in the same manner heretofore dis-

cussed with respect to the device 10, and may be applied to a fingernail in the same manner heretofore set forth with respect to the device 10. The principal difference between the device 10a and the device 10 is that the device 10a is constructed of a body member 12a and a waterproof adhesive 14a, the body member 12a being constructed of a suitable plastic such as, for example, cellulose acetate impregnated with the color desired in the finished nail. Such colors, of course, may range from practically colorless transparent plastic, to afford little more than a high sheen to the fingernails to which applied, to a dark red, translucent plastic simulating the present popular dark red colors of fingernail polish now being applied in liquid form directly to the nails.

It will be understood, of course, that cellulose acetate is set forth merely by way of illustration and not by way of limitation and that other plastic materials having the desired physical and chemical characteristics may be used, other examples of suitable plastics being, rubber hydrochloride sheets known in the trade as "Pliofilm," and flexible polystyrene sheets known in the trade as "Polyflex," among others.

The waterproof adhesive 14a applied to the bottom face of the plastic body member 12a may be any suitable type such as, for example, the same type of adhesive 14, previously discussed.

From the foregoing it will be seen that I have afforded a novel manicuring device which is water-proof in character, protects the fingernails from chipping and cracking, is quickly and easily applied, removed, and reapplied, and affords a novel practical and efficient coating for fingernails which may be quickly and easily applied by the average individual and when so applied affords the lustrous, highly polished appearance that is now being sought by many individuals especially women, in the application of liquid polishes to their nails.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. An article of manufacture comprising a flexible substantially flat base sheet of woven fabric impregnated with material making the same water-repellent, said base sheet being preformed into substantially the shape of a flattened nail on a digit of a human and having a smooth upper face, a tacky, water-repellent, pressure-sensitive adhesive on the bottom face of the base sheet for securing the same to the nail, and a film of dried nail polishing material on and covering the smooth upper face of the base sheet, said base sheet acting as a pad to cushion the film of dried nail polishing material against shock from impact of the nail with hard objects and thereby preventing chipping of said film of dried nail polishing material.

2. An article of manufacture comprising a transparent, flat backing sheet of substantially open-mesh fabric, a base sheet mounted on the backing sheet, said base sheet being preformed into a size and shape corresponding to that of a flattened nail of a human digit, a pressure-sensitive adhesive material on one face of the

base sheet releasably securing the base sheet to the backing sheet, said backing sheet being sufficiently larger than the base sheet so that the backing sheet extends a substantial distance beyond the marginal edge of the base sheet whereby the transparent backing sheet may be grasped and positioned over the finger nail of an individual for comparison of the size of said base sheet therewith prior to removal of the base sheet from the backing sheet.

10 LILA G. TERRY.
